UNITED STATES PATENT OFFICE.

FRANZ A. FULLER, OF NEWARK, NEW JERSEY.

DESIGN FOR A RAZOR-BLADE.

45,908.

Specification for Design.

Patented June 9, 1914.

Application filed November 26, 1913. Serial No. 803,340. Term of patent 14 years.

To all whom it may concern:

Be it known that I, FRANZ A. FULLER, a citizen of the United States, residing in the city of Newark, in the county of Essex and State of New Jersey, have invented a new and useful Design for Razor-Blades; and I do hereby declare the following to be a full, clear, and exact description of the invention, such as will enable others skilled in the art to which it appertains to make and use the same, reference being had to the accompanying drawings, and the letters of reference marked thereon, which form a part of this specification.

As shown in the drawings, the leading or material feature of my design consists in a detachable ornamental razor blade made of sheet steel, provided with a substantially plane longitudinal portion *a*, and having a longitudinal cutting edge *b*, said edge lying

approximately in an extension of said plane portion *a*, the blade intermediate said portion in said edge, comprising a portion *c* inclined from said edge away from the central plane of said first mentioned portion and lying entirely on one side thereof, and an off-set portion *d* connecting said inclined portion with said first mentioned portion, the lines of union between said off-set portion and said other portion being straight lines approximately parallel to said cutting edge.

I claim:

The ornamental design for a razor blade as shown and described.

FRANZ A. FULLER,

Witnesses:

W. H. CONKLIN,
FREDK. C. FISCHER.
